[57] **CLAIM**

The ornamental design for an adjustable copy holder for attachment to a portable computer, as shown and described.

DESCRIPTION

FIG. 1 is a top, left front perspective view of an adjustable copy holder for attachment to a computer monitor showing my new design in an extended condition;

FIG. 2 is a top, right front perspective view in a folded condition;

FIG. 3 is a front elevational view in a partially extended condition, drawn to an enlarged scale with respect to FIG. 1;

FIG. 4 is a rear elevational view of FIG. 3;

FIG. 5 is a top plan view of FIG. 3 drawn to an enlarged scale with respect thereto; and.

FIG. 6 is a bottom plan view of FIG. 5.

The open portable computer in FIG. 1 and the closed portable computer in FIG. 2 have been depicted by means of broken lines for illustrative purposes only and form no part of the claimed design.
